CLAIM

I claim the ornamental design for a drone, as shown and described.

DESCRIPTION

FIG. 1 is a perspective view of the drone embodying my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the drone embodying my new design with the four propellers tilted in an alternate configuration of use;

FIG. 9 is a front elevational view of FIG. 8;

FIG. 10 is a left side elevational view of FIG. 8, with the right side elevational view being a mirror image thereof;

FIG. 11 is a perspective view of the drone embodying my new design with the four propellers tilted into another configuration of use;

FIG. 12 is a front elevational view of FIG. 11;

FIG. 13 is a left side elevational view of FIG. 11, with the right side elevational view being a mirror image thereof;

FIG. 14 is a perspective view of the drone embodying my new design with the four propellers tilted into a further configuration of use;

FIG. 15 is a front elevational view of FIG. 14; and,

FIG. 16 is a left side elevational view of FIG. 14, with the right side elevational view being a mirror image thereof.

The broken lines depict portions of the drone that form no part of the claim.

1 Claim, 16 Drawing Sheets
